UNITED STATES PATENT OFFICE.

CHARLES H. KNAPP, OF PATERSON, NEW JERSEY.

WINDING-MACHINE.

SPECIFICATION forming part of Letters Patent No. 748,750, dated January 5, 1904.

Application filed March 4, 1903. Serial No. 146,054. (No model.)

To all whom it may concern:

Be it known that I, CHARLES H. KNAPP, a citizen of the United States, residing in Paterson, in the county of Passaic and State of New Jersey, have invented certain new and useful Improvements in Winding-Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to winding-machines; and it has reference particularly to that class of winding-machines wherein provision is made for compensating for the tendency of the beam or spools, as the case may be, to draw on the threads with gradually-increasing tension owing to the increase in the thickness of the goods wound.

My invention, which has in view as its principal object improving the rotating means for the beam or spools and also the traverse mechanism, will be found fully illustrated in the accompanying drawings, wherein—

Figure 1 is a side view of enough of the machine constituting my invention to illustrate the improvements thereon. Fig. 2 is a top plan view of what is shown in Fig. 1. Fig. 3 is a slightly-enlarged front view of a portion of the machine, and Fig. 4 illustrates a detail.

In a frame *a*, which is braced in part by plates *b* and *c* and by the usual pair of guide-rods *d*, is journaled the drive-shaft *e*, which carries a face-plate *f* at one end and receives the power through a pulley *g* or the like at the other end. Above this shaft is journaled a counter-shaft *h*, which is connected by gearing *i*, inclosed in a casing *j* with a traversing mandrel *k*, which is splined with the gear *l*, forming one of the members of gearing *i*. The power is transmitted from face-plate *f* to shaft *h* through a vertical shaft *m*, which is journaled in the bearings *n*, carried by a stand *o*, which projects from the side of the frame, said shaft having splined onto it a friction-disk *p* and being connected with shaft *h* by bevel-gearing *q*. The action of face-plate *f* is initially imparted to the friction-disk from a controlling-lever *r*, which is con-

nected with shaft *e* by any suitable mechanism (not shown)—for instance, such as that illustrated in my United States Letters Patent No. 661,268, which operates to shift the shaft *e*, and consequently the face-plate, toward the friction-disk. Friction-disk *p* may be adjusted so as to take various speeds of rotation from the face-plate from a hand-wheel *s*, which is journaled in the frame and is connected with the friction-disk by a pinion *t*, rotating with the hand-wheel, a lever *u*, fulcrumed in the frame and having a segmental rack *v*, meshing with the pinion, and a fork *w*, which engages a grooved collar *x* on the friction-disk and which has a sleeve *y*, which is guided on an upright *z* of stand *o* and is connected with the free end of lever *u* by a link *l*.

In the frame *a* and a bracket *2*, which is adjustably secured on the rear guide-rod *d*, is arranged for longitudinal movement a shaft *3*, which carries fork *4*, adjustably secured on the shaft by set-screws *5* and receiving the mandrel *k* against the outside of collars *6*, on which said forks take. On the free end of shaft *3* is arranged between collars *7* on the shaft an arm *8*, said arm being pressed toward one of the collars by a spiral spring *9*, interposed between the arm and the other collar. The arm may be kept in the approximately vertical position shown by a key *10* on the collar *7*, with which said arm engages, said key engaging a groove *11* in the adjoining face of the arm. This arm forms the bearing for one end of the spindle or other axial support *12*, on which the spools *13* are directly mounted, the other end of the spindle being secured in the mandrel in such manner as to have imparted to it the rotary action of the mandrel.

14 represents the thread-guides, carried by a suitable support *15* in parallel disposition to the spools.

In view of the foregoing it will be manifest that any longitudinal reciprocation of the supporting means (comprising mandrel *k*, forks *4*, shaft *3*, arm *8*, and spindle *12*) for the spools will be imparted to the spools simultaneously with their being rotated from mandrel *k*, the thread-guides acting to lay the goods evenly on the spools as the latter are caused to rotate and traverse.

Shaft *3* carries a bracket *16*, secured adjust-

ably thereon by means of a set-screw 17 and through which the shaft is normally pulled in one direction by means of a weight 18, which is connected with the bracket by means 5 of a flexible connection 19, passing over a pulley 20, journaled in the frame.

21 is a stand secured to plate *b* and having a vertical slot 22. In this slot is guided a block 23, having a flange 24, which takes 10 against the rear face of the stand and is formed with a stud 25, onto which is screwed a nut 26, which holds in place a plate 27, which takes against the front face of the stand. The block is penetrated and engaged 15 by a screw 28, having bearings in the stand and capable of being rotated from a hand-wheel 29 on a shaft 30, journaled in the upper end of the stand through bevel-gearing 31. A stud 32 on block 23 forms a fulcrum for a 20 lever 33, which is formed with a longitudinal slot 32', receiving the stud, and whose upper end is forked and receives an antifriction-roller 34 on the bracket 16, its lower end having another antifriction-roller or other projection 25 35, moving in guides 35' in the stand and engaging a cam 36 on a shaft 37, which is journaled in a stand 38, carried by the plate *c*. By altering the position of stud 32 by vertically adjusting block 23 from hand-wheel 30 29 the fulcrum for the lever 33, which is formed by said stud, is altered, and so the throw of the upper end of the lever is varied, thus varying the length of the traverse of the spools.

35 The cam 36, which actuates lever 33, is driven through shaft 37 from a worm-wheel 39 on said shaft, which meshes with a worm 40, carried by a shaft 41, having bearings in an oil-cup 42, carried by plate *c*, said shaft 40 41 and another shaft 43 carrying cone-pulleys 44, around which extends a belt 45. Shaft 43, which is journaled in the frame *a*, is driven from shaft *h* through a sprocket-and-chain arrangement 46. In order to vary the speed 45 of shaft 37, and consequently the rapidity of the traverse, I provide a belt-shifter 47, which is penetrated by and has a threaded engagement with a shaft 48, journaled in frame *a* and rotated from a hand-wheel 49 on a shaft 50 50 through the medium of bevel-gearing 51. The belt-shifter carries at one end a fork 52, which receives the under stretch of the belt, and at the other end a roller 53, which takes against the upper stretch of the belt. Shaft 55 50 is journaled in brackets 54 and 55, respectively, carried by frame *a* and plate *c*. It will be manifest that by manipulating the hand-wheel the belt may be shifted so as to vary the relative speeds of shafts 43 and 37, and 60 consequently the rapidity of the traverse, as above stated.

Having thus fully described my invention, what I claim as new, and desire to secure by Letters Patent, is—

65 1. The combination of a frame, the device

or devices on which the material is wound, a face-plate, a rotary shaft, power-transmitting mechanism operatively connecting the shaft and said device or devices, a friction-disk splined on the shaft and adapted to be engaged by the face-plate, a rotary toothed part, a lever having a segmental toothed portion engaging said toothed part, and operative connecting mechanism between the lever and the friction-disk, substantially as described. 70 75

2. The combination of a frame, the device or devices on which the material is wound, a face-plate, a rotary shaft, power-transmitting mechanism operatively connecting the shaft and said device or devices, a friction-disk 80 splined on the shaft and adapted to be engaged by the face-plate, a rotary toothed part, a lever having a segmental toothed portion engaging said toothed part, a fork engaging the friction-disk, a guiding part penetrating 85 a portion of the fork, and operative connecting means between said lever and the fork, substantially as described.

3. The combination of a frame, for the device or devices on which the material is wound, an axial support therefor, a longitudinally-movable shaft guided in said frame, a longitudinally-movable mandrel also guided in the frame, means connecting the shaft and the mandrel for transmitting from the one to the other longitudinal movement, and a spring-actuated arm arranged on said shaft and co-active with said mandrel for sustaining the axial support of said device or devices, substantially as described. 90 100

4. The combination of a frame, for the device or devices on which the material is wound, an axial support therefor, a longitudinally-movable shaft guided in said frame, a longitudinally-movable mandrel also guided in the 105 frame, means connecting the shaft and the mandrel for transmitting from the one to the other longitudinal movement, and means, carried by said shaft and coacting with the mandrel, for sustaining the axial support of 110 said device or devices, substantially as described.

5. The combination of a frame, the device or devices on which the material is wound, a traversable support for said device or devices 115 guided in the frame, a lever engaging said support, means for actuating the lever, a slotted stand carried by the frame, a block arranged to move in the slot, said lever having a fulcrum in the block, and a rotary threaded 120 shaft engaging the block, substantially as described.

In testimony that I claim the foregoing I have hereunto set my hand this 2d day of March, 1903.

CHARLES H. KNAPP.
